UNITED STATES PATENT OFFICE

ARTHUR HERBERT CHARLTON, OF BRENTFORD, ENGLAND, ASSIGNOR OF ONE-HALF
TO T. B. ROWE AND COMPANY, LIMITED, OF BRENTFORD, ENGLAND

PRODUCTION OF SOAP THREADS

Application filed November 1, 1926, Serial No. 145,623, and in Great Britain November 24, 1925.

This invention relates to the manufacture of soap threads and the like, for example soap in ribbon form.

At the present time the manufacture of high-class soap in this form is usually carried out by converting liquid soap into ribbon form either by cooling it on a drum or by forming it into bars and then drying it, after which it is milled into flake form.

10 It has, however, been proposed to treat soap for the production of thin threads of the nature of vermicelli by forcing it in a sufficiently soft condition through dies in an apparatus resembling the ordinary plodder used 15 in forming cakes of soap.

Proposals for the manufacture of soap in powder form have also been made especially for the production of washing powders by spraying or atomizing processes. Such powders as ordinarily made usually contain a considerable admixture of alkali.

It has also been proposed to utilize a spraying and drying method for the formation of an atomized soap to be subsequently pressed 25 to form an aerated or floating soap.

The object of the present invention is to provide an improved process of manufacturing finely-divided soap.

The invention consists in a method of preparing soap which comprises the forcing of 30 liquid soap under suitable pressure with or without other ingredients through suitable orifices for the formation of solidified filaments or ribbons.

35 The invention also consists in soap in filament or ribbon form when prepared according to processes indicated herein.

Referring to the accompanying drawings:—

40 Figure 1 is a diagrammatic representation of one form of apparatus for carrying the invention into effect, where pressure is obtained by means of a rotary pump.

Figure 2 is an illustration of soap pumped 45 whilst molten through a small orifice by the apparatus shown in Figure 1.

Figure 3 is an enlarged view of elements of Figure 2.

50 Figure 4 is a modification where centrifugal force is employed.

Figure 5 is an enlarged view of soap forced through small holes by centrifugal force, namely by the apparatus of Figure 4.

In carrying the invention into effect in the form illustrated in Figure 1, liquid soap *a* at a 55 temperature at which soap is usually taken from the boiling pan and of materials which readily solidify on exposure and of ordinary concentration, that is containing about 63 per cent fatty acids, is drawn from a container *b*, by the rotary pump *d*.

60 It is discharged by this pump through the holes *e* about $\frac{1}{4}$ mm. diameter. The pressure of discharge is indicated by the gauge *f* and may be about 30 lbs. per square inch. As a 65 result, solidified soap in filamentous form is obtained, as illustrated in Figure 2.

The filaments are discontinuous and of varying length, those shown being of the order from $\frac{1}{4}$ inch to an inch in length.

70 When freshly prepared the filaments are of somewhat uneven diameter, having the appearance shown, for example, in Figure 3.

The invention is not limited to the size of discharge orifice indicated or to a pressure of 75 the amount indicated above, because variations may be made, having regard, for example, to the type of soap it is desired to produce, the temperature used and the output required.

80 Care should be taken that the pressure is sufficiently high to force the soap through the holes to provide the desired filaments or ribbons on solidification.

The pressure may be conveniently between 85 15 and 60 lbs. per square inch. It may be obtained in any suitable way, for instance, by the direct pressure of a pump or by a pressure vessel or by centrifugal force.

Figure 4 illustrates an apparatus by which 90 the pressure may be obtained by centrifugal force.

In this apparatus the soap *a* is contained in a cylindrical vessel *g* having a number of holes *h* in its periphery, of diameter about $\frac{1}{4}$ mm. The vessel *g* is provided with a filling aperture *m* through which molten soap can be fed by means of the tap *n*. The vessel is supported on a pivot *i* and guided by an upper bearing *j*.

It is rotated at high speed by means indicated as a grooved pulley *k* and driving band *l*. A convenient speed for purposes of the present invention is 3,500 revolutions per minute.

5 Figure 5 illustrates the appearance of soap which has been freshly prepared by this method.

General

10 If desired soap previously aerated may be used.

As regards the number of holes, this also depends on requirements. I find it convenient to use from 30 to 50 holes in a circular area of about 1½ inches diameter, but this is not essential.

15 The size of the holes may be varied to give, for instance, filaments or ribbons up to a thickness of about 1 mm. the width of the ribbons varying, for instance, up about 1" according to the thinness of the ribbon formed.

20 Having regard to the size of holes through which extrusion takes place the filtering operation frequently employed in soap manufacture should be carefully conducted in order to avoid choking of the orifices.

25 The soap may be extruded in any convenient direction, for example, the soap may be propelled substantially horizontally or in a downward direction and the length of travel should be so chosen that the filaments are sufficiently solidified.

30 35 If desired the liquid soap may be discharged into cooled air or if desired into air warmed for drying purposes. By the introduction of cold air at the bottom of the extrusion chamber the effect of counter-current cooling may be obtained.

40 The solidified filaments or ribbons may be caused to fall directly into a conveyor or on to a conveyor band.

I prefer that the cooling on extrusion 45 should be the first consideration and the operation of drying be subsequently effected for instance by means of warm or dry air, so as to form a soap having the necessary percentage of fatty acids for a high-class toilet soap.

50 The fatty acid content of the soap may be varied and other ingredients preferably in liquid form or in solution and compatible with soap, for example, sodium carbonate or silicate of soda may be mixed therewith before extrusion if desired.

55 Having now described my invention, what I claim as new and desire to secure by Letters Patent is:—

60 Process of producing filaments of soap from hot liquid soap of a temperature at which soap is usually taken from the boiling pan and of materials which readily solidify upon cooling, which comprises passing such 65 hot soap through a conduit and forcing same

through a fine orifice into a cooling atmosphere the soap being continuously cooled by radiation during its passage through such conduit.

In testimony whereof I have signed my name to this specification.

ARTHUR HERBERT CHARLTON.
